UNITED STATES PATENT OFFICE

HAROLD R. MURDOCK, OF CANTON, NORTH CAROLINA, ASSIGNOR TO THE CHAMPION FIBRE COMPANY, OF CANTON, NORTH CAROLINA, A CORPORATION OF OHIO

PROCESS FOR EXTRACTING WATER-SOLUBLE SUBSTANCES FROM RAW FIBROUS MATERIALS CONTAINING THE SAME, AND FOR SIMULTANEOUSLY FORMING THE FIBROUS MATERIALS INTO A WEB, AND SYSTEM OF APPARATUS THEREFOR

Application filed September 26, 1930. Serial No. 484,688.

This invention relates to processes for extracting water-soluble substances from fibrous materials containing the same, and is concerned with an interrelated process for extracting water-soluble constituents and forming a fibrous web from fibrous paper-pulp-yielding materials and with a system of apparatus adapted to the carrying out of the said process.

10 More particularly, this invention finds application to an extraction treatment of a fibrous material, such, for instance, as the woody part of the oak, hemlock or chestnut, containing water soluble constituents adapted for use as tanning agents, or of the larch, whose water-soluble constituents contain valuable chemicals, such as galactan, whereby the fibrous materials after extraction are in the condition, and possess the characteristics, inherently necessary in a web-forming pulp.

In processes heretofore known and used, the raw fibrous materials containing water-soluble ingredients are reduced in their natural, relatively dry, condition by mechanical means to a comminuted state, and the comminuted material is extracted by being brought into contact with water on the principle of counter-current flow. In order 20 to secure, in a reasonable length of time, an adequate degree of removal of the water-soluble substances present in the fibrous materials, it has been considered necessary to bring the materials to a relatively fine state 25 of comminution. It has been the practice to maintain the extractant at any suitable temperature favorable to the production of an extract of a desired degree of purity. In those cases where the extractant was main-

30 tained at a temperature at or above 212° F., the extraction was effected in pressure containers; at working temperatures below 212° F., open tanks or tubs were employed. This fine subdivision of the fibrous materials in 35 their natural, relatively dry, state resulted in the production of a product containing a large proportion of powdered material and of fibrous particles in which the ultimate fibers and fiber bundles were greatly shortened, with the result that, after extraction,

the by-product fibrous materials no longer had value as raw materials for paper pulp.

According to one process by which the fibers are preserved more nearly in the natural length, the materials are chipped or cut so that they are, for example, passed through a one inch screen and are retained on a one quarter inch screen. It has been found that by using chips of this size the resulting pulp possesses reasonably good fiber, but the process of extraction of the water-soluble constituents is made necessarily difficult and requires the use of pressure autoclaves with water at high temperature. This forced extraction produces a dark colored extract and involves considerable labor, equipment and difficulties in operation.

An object of the present invention is to provide a process by which to obtain relatively lighter colored extracts while preserving the fibrous nature of the raw materials and the relative length of the natural fibers. Another object of the invention is to provide an extraction and pulping process by which to obtain a desirable extract and a desirable paper-forming pulp, which process involves no difficult operations or complicated and expensive equipment and requires but little labor. A further object of the invention is to provide a system of apparatus adapted for use in such a process.

The crux of the present invention may be said to reside in fibrilating the raw fibrous material containing water-soluble extractives in a grinding operation in the presence of aqueous liquid, extracting from the resulting pulpy mass water-soluble substances contained therein, and forming the pulp freed of water-soluble substances into a web.

The first step of my process consists in fibrilating the raw fibrous material (e. g., wood) containing valuable water-soluble substances by a grinding operation. This operation may be effected in an apparatus such as is used commonly in the preparation of ground wood pulp. This apparatus usually comprises a rotating stone in which are cut grooves to act as cutting surfaces and imbed the fibers after they are cut from the material.

being fibrilated. The fibrous materials are held in position on the rotating stone by one or more devices comprising a pocket or compartment and a pressure-supplying plunger for forcing the raw material against the stone to produce fibrillation. The rotating stone is partially immersed in a trough filled with water so that the fibers are washed from the grooves in the stone and retained in the trough. Showers are also directed on the stone to further clear the cutting surfaces. Due to the heat of grinding, it is possible to maintain an elevated temperature in the trough by regulating the amount of shower water used on the stone.

In the trough the extraction process becomes active. The pulpy mass thus produced is moved through the trough by means of the rotating stone, and overflows from one end of the trough into a pit or reservoir due to the continued additions of water and fibrous materials on the cutting surfaces of the stone.

Should satisfactory extraction of the water-soluble ingredients not be effected by the time the fibrous materials enter the pit it is sometimes necessary to use a stock chest, whereby the fibers are maintained in direct contact with water at a more or less elevated temperature for a sufficient length of time to obtain satisfactory removal of the water-soluble ingredients. The pulpy mass comprising pulp fiber and valuable water-soluble extract, which overflows from the trough, or the contents of the pit and stock chest (if used), may be screened in order to remove the coarser fibers from the pulp.

The slushed pulp is then conveyed with the water-soluble extract to a web-forming device, such as a thickener, in order to separate the pulp from the water-soluble extract. At this point the pulp leaves its initial extracting medium, passing, preferably, to a diffusing battery where it is washed counter-currently by the well known principle in order to effectively obtain the water-soluble extractive materials which have been made readily available by the previously mentioned pulping operation. The water solution coming from the thickener, which solution contains valuable water-soluble ingredients of the fibrous materials, may be returned to the grinder for reuse. It may likewise be used to dilute the slushed pulp coming from the grinder where it enters the pit or in the stock chest or at the screen, or it may be diverted to a suitable evaporating device if and when sufficiently concentrated as to its content of dissolved solids.

The pulp, which comes from the thickener in the form of a web, may be used as such for many purposes, so that a cylinder, or Fourdrinier, paper making machine may be used effectively as the thickening device. Where this is contemplated I may, and preferably

do, add to the pulp moving to the paper machine a suitable amount, say 20% or more, of a suspension of longer-fibered pulp, such for instance as that produced by a chemical pulping process, whereby to alter or modify the characteristics of the resulting web, e. g., to strengthen the same. The addition, at this same stage of the process, of known paper making ingredients such as, for example, a sizing agent and/or a filler, likewise is contemplated. Since it might be found more expedient to wash the thickened pulp the more nearly completely to remove water-soluble ingredients by the aforementioned countercurrent leaching procedure, it may, as above indicated, be found more practical to interpose a diffusing battery between a primary thickening device and the aforesaid web-forming device, and to reuse the water solution coming from the diffuser and the second thickener for make-up water in the grinding operation.

It should be apparent from the above that the described extraction system is cyclic and continuous, since the relatively concentrated extractant, hereinafter called "strong liquor", may be removed from the system as desired and used as such or evaporated to a more concentrated product.

Thus the relatively concentrated extractant, or "washings", may be bled (continuously or intermittently) to the evaporators, and condensate from the evaporators may be returned to the cyclic system at any desired point,—for instance, to the diffusing operation, to the grinding operation, as diluent of the freshly ground pulpy mass, or wherever else in the series of operations it may be found desirable to introduce water.

This process for extracting water-soluble materials is found to yield efficiently a much better and lighter colored product than that which it has been possible to obtain by the older methods. This is a decided advantage, especially in those cases where the extractive materials are tanning agents. It has been found quite impossible to obtain a light color when tanning hides due to the coloring ingredients present in the vegetable tanning solution obtained by such extraction, unless such tanning materials were treated previously to remove the deleterious coloring materials. By my process an extractant is obtained which makes further treatment unnecessary in the obtaining of an extract adapted for use in the production of light colored tanned hides.

In the grinding of pulp by what is commonly known as the ground wood method a great deal of energy is dissipated in the form of heat which, so far as I am aware, has never been utilized satisfactorily. It should be apparent that the present process utilizes the heat to a decided advantage, the heat assisting decidedly in the rate of removal of the water-soluble ingredients.

In the extraction of woody materials, for example, chestnut wood, by this process, a temperature between 70° F. and 200° F. has been found suitable, but in practice a temperature of about 150° F. will be found desirable. The water extractant which circulates through the system in cyclic manner will be found suitable for evaporation when its total solid content is around 2%, but in some cases it will be found desirable to maintain a concentration of total solids in the circulating system of extraction higher than 2%. The ratio of fibrous material to extractant depends entirely on the nature of the fiber and water-soluble constituent desired. The usual relationship used in ground wood products will be found satisfactory in practice of this process.

In order that the invention may be better understood, reference is made to the accompanying drawing, which is a diagrammatic representation of a system of apparatus for carrying out the above-described process.

In the drawing 1 represents a wood grinding machine of conventional design, including a trough 1a; 2 represents a pit, and 3 a stock chest, for the reception of pulpy mass from grinder 1; 4 is a screening device for the separation from the pulpy mass of slivers 30 knots, and coarser fiber bundles; 5 is a thickening device, of conventional design, for the reduction of the liquid content of a pulpy mass; 6 diagrammatically represents a battery of diffusers or counter-current washers; 35 7 is a thickening device which may and preferably does take the form of a paper-making machine such as a cylinder machine or Fourdrinier machine; and 8 represents an evaporator. By means of a suitable system 40 of piping aqueous liquid may be supplied to grinder 1, pit 2, stock chest 3, or screens 4, either from an outside source of aqueous liquid or from thickeners 5 and 7 or diffusers 6. Likewise, the extractant may be diverted to 45 evaporator 8 from thickeners 5 or 7 or diffusers 6.

While in the foregoing the device for fibrilating the raw fibrous material has been described as being a wood grinding machine 50 of conventional design, it is not my intention to exclude the use of other equivalent means for grinding wood to obtain a fibrous pulp. Thus, for instance, I may with like results make use of a device wherein wood 55 chips are fibrilated between rotating discs, or of any other means similar to that illustratively described hereinbefore.

In carrying out the operations of the process using the above-described apparatus, the 60 fibrous materials, such as wood, are fed into the pockets of the grinder (1), where they are fibrilated by means of the rotating stone, in the presence of aqueous extractant, and in company with the water solution they fall into the trough (1a), directly below the

grinder proper and then, after an interval, the pulp, in a comparatively high consistency, overflows into the pit (2). At this point the pulpy mass may be diluted to a lower consistency and passed on to the stock 70 chest (3). This stock chest may or may not be used, depending upon the efficiency and ease of removal of the water-soluble ingredients in the initial grinding operation. The stock chest is preferably capable of maintaining an elevated temperature to assist the extraction process. The pulp and its water extractant is then passed onto screens (4), whereby the coarser fibers are removed and the isolated finer fibers in their medium of water extractant are passed to a thickener (5). The water extractant at this point is returned to the grinding operation, or used in dilution at the pit, stock chest or screens. When the solution becomes concentrated enough it may be continuously withdrawn, as is shown in the diagram, as "strong liquor" for evaporation. Condensate from the evaporators may be returned to the cycle at any point where addition of fresh water has been indicated. The pulp passing from the thickener (5), is conveyed to a diffuser (6), whereby it is washed with water counter-currently and freed of water-soluble constituents. The washings from the diffusing operation may be used as makeup water in the grinding operation, or elsewhere as may be found practical, in order to recover the valuable ingredients which they contain. The pulp coming from the diffusers is passed to a thickener 75 (7), which may be, and preferably is, a paper making machine. At this point the pulp forms a continuous web which is substantially free of water-soluble ingredients and possesses fiber length comparable to pulp made from such wood by any of the well known chemical pulping processes.

I claim:

1. Process for recovering water-soluble substances from raw fibrous material containing the same and for simultaneously preparing said material in the form of a paper web, which includes the following steps: (a) grinding the raw fibrous material in the presence of aqueous liquid, (b) subjecting the resulting fibrilated material to prolonged contact with said aqueous liquid whereby to promote solution in the liquid of the water-soluble substances contained in the material, (c) at least partially separating the resulting aqueous solution from the fibrilated material, (d) subjecting the separated fibrilated material to prolonged treatment with an aqueous liquid, (e) separating the treated fibrilated material from the resulting aqueous solution and simultaneously forming said fibrilated material into a paper web and washing the latter while retaining the separated aqueous solution and the washings, (f) using a portion of the retained aqueous solu-

- tion from the steps (c) and (e) as aqueous liquid in one of the steps (a) and (b) and from the remaining portion of the retained aqueous solution from steps (c) and (d) separating water whereby to yield a concentrated extract of the aforesaid water-soluble substances, and (g) using the water separated in step (f) as at least a part of the aqueous liquid in one of the steps (b) and (d).
- 5 2. A system of apparatus for extracting water-soluble substances from raw fibrous materials containing the same and for simultaneously preparing the fibrous material in the form of a web, which comprises, in co-
10 operation, means for fibrilating raw fibrous material in the presence of aqueous liquid whereby to yield a pulpy mass of the material, means for holding fibrilated material in prolonged contact with aqueous liquid, means for
15 delivering pulpy mass from the aforesaid fibrilating means to said contacting means, means for separating aqueous liquid from fibrilated material, means for delivering pulpy mass from said contacting means to
20 said separating means, a second means for holding fibrilated material in prolonged contact with aqueous liquid as a pulpy mass, means for delivering separated fibrilated material from the aforesaid separating means
25 to said second contacting means and means for delivering aqueous liquid to the latter, means for separating fibrilated material from aqueous liquid and simultaneously forming the fibrilated material into a web, means for
30 delivering pulpy mass from said second contacting means to said separating and web-forming means, an evaporator, means for delivering aqueous liquid from at least one of said separating means to said evaporator and
35 for delivering condensate from said evaporator to at least one of the following: the fibrilating means, the separating means, and the second contacting means.
- 40 In testimony whereof, I affix my signature.
